CLAIM

I claim the ornamental design for a food cone, as shown and described.

DESCRIPTION

FIG. 1 is a front elevational view of the food cone of the present invention;

FIG. 2 is a top plan view thereof;

FIG. 3 is a bottom plan view thereof;

FIG. 4 is a right side elevational view thereof;

FIG. 5 is a left side elevational view thereof; and,

FIG. 6 is a rear elevational view thereof.
